DESIGN FOR A FINGER RING

Charles Van Brunt Reilly, Milwaukee, Wis.

Application January 1, 1945, Serial No. 117,208

Term of patent 3½ years

(Cl. D45—10)

To all whom it may concern:

Be it known that I, Charles Van Brunt Reilly, a citizen of the United States, residing at Milwaukee, in the county of Milwaukee and State of Wisconsin, have invented a new, original, and ornamental Design for Finger Ring, of which the following is a specification, reference being had to the accompanying drawing, forming part thereof; and in which:

Fig. 1 is a front elevational view of a finger ring showing my new design,

Fig. 2 is a top plan view, and

Fig. 3 is a side elevational view thereof.

I claim:

The ornamental design for a finger ring, as shown.

CHARLES VAN BRUNT REILLY.
